COMBINED LIGHT SOCKET AND CLIP

Roger E. Peterson, Bovey, Minn.

Application October 14, 1957, Serial No. 48,092

Term of patent 14 years

(Cl. D29—1)

Fig. 1 is a perspective view of a combined light socket and clip, showing my new design;

Fig. 2 is a side elevational view thereof on a reduced scale; and

Fig. 3 is a reduced rear elevational view thereof.

The broken lines showing of a light bulb and a portion of a cord is for illustrative purposes only.

I claim:

The ornamental design for a combined light socket and clip, as shown and described.
